No. 758,937.

PATENTED MAY 3, 1904.

M. SARFERT.
SINGEING MACHINE.
APPLICATION FILED MAR. 10, 1900.

NO MODEL.

UNITED STATES PATENT OFFICE.

MAX SARFERT, OF PHILADELPHIA, PENNSYLVANIA, ASSIGNOR TO THE SARFERT COMPANY, A CORPORATION OF NEW JERSEY.

SINGEING-MACHINE.

SPECIFICATION forming part of Letters Patent No. 758,937, dated May 3, 1904.

Application filed March 10, 1900. Serial No. 8,141. (No model.)

To all whom it may concern.

Be it known that I, MAX SARFERT, a citizen of the United States, residing in the city and county of Philadelphia, State of Pennsylvania, have invented a new and useful Improvement 5 in Singeing-Machines, which improvement is fully set forth in the following specification and accompanying drawings.

My invention relates to the art of singeing 10 textile fabrics; and it consists of a machine for singeing the outside or outer surface of hollow or tubular articles—such, for instance, as hosiery—for the purpose of removing the fuzz, nap, or lint from the outer surface only 15 thereof, and thus to impart to the article a finished appearance.

My invention further consists of novel details of construction hereinafter fully described and claimed.

20 Figure 1 represents a side elevation of a singeing-machine embodying my invention. Fig. 2 represents a front elevation of Fig. 1, a portion thereof being shown in section. Fig. 3 represents a front elevation of the burner-tubes, showing the air-valve in section. Fig. 25 4 represents a plan view of a form to be inserted in the article to hold the same in position when being singed.

Similar numerals of reference indicate 30 corresponding parts in the figures.

For the purpose of illustrating my invention I have shown a machine for singeing hosiery, as this example best illustrates the principle of my invention, and since my invention has been particularly designed for 35 singeing hosiery and in accordance with the broad principle thereof I employ two principal instrumentalities—namely, means for supporting the stocking or other article from 40 within and, second, a singeing means, these two means being preferably relatively movable, so as to apply the singeing means to the outside of the stocking to singe substantially the entire outer surface thereof. It is obvious 45 that these principal instrumentalities of which my invention consists can be variously arranged and organized, and in the accompanying drawings I have shown one simple embodiment thereof which I have found in practice to

be successful and which consists in employing 50 two burners arranged to project their flames toward each other, a pair of driven rollers situated next to these burners, so that when a stocking and a form placed therein to hold said stocking flat is inserted between these 55 rollers said form and surrounding stocking is projected between the burners and the outside of the stocking or its entire outer surface is subjected to the singeing agent, although it is understood that my invention is not limited 60 to this specific arrangement and organization of these instrumentalities. I will now proceed to describe the specific construction shown in the accompanying drawings.

1 designates the feeding-table, which may, 65 although not necessarily, be employed and which is supported in any suitable manner in proximity to the feed-rollers 2 and 3, which are mounted on the shafts 4 and 5, which revolve in suitable bearings in the framework 70 or housing 6. The shaft 5 is mounted in stationary bearings, while the shaft 4 is mounted in boxes or bearings 7, above each of which is a resilient or yielding cushion 8, upon which rests the plate 9, against which bears the bolt 75 10, which passes through a suitable portion of the housing and is locked in the desired position by the jam-nut 11. The shaft 4 and the feed-roller 2 thereon are rotated by any suitable means, as the belt 12 and pulley 13, 80 and power is transmitted from said shaft 4 to the gear 14, which meshes with the gear 15, mounted on the shaft 5, whereby the latter and its roller are actuated in unison with the roller 2. At the discharge side of the feed-rollers are located the upper and lower burner-tubes 16 and 17, respectively, which are supported in any suitable manner and receive the gas or vapor from the supply-pipe or vaporizer 18, the admission of the proper amount 90 of oxygen being regulated by a suitable valve 19, (seen in Fig. 3,) it being understood that each of the burner-tubes are provided with suitable valves 20 and 21, whereby the supply of vapor can be readily regulated.

95 It will be noted that the discharge jets or openings 22 in the upper burner-tube 16 are out of alignment with the jets 23 in the lower

burner-tube and are so arranged that one flame is directed downwardly and the other upwardly, the downward flame in the present instance being in advance of the upper flame, 5 whereby the flames are not directed to a common point, thus minimizing the danger of the flames uniting, and thus burning or scorching the articles passed between them.

In practice I have found it preferable to 10 make the upper burner-tube 16 of greater diameter than the lower burner-tube 17, the jet-openings 23 in the latter being of less size than the jet-openings 22, it being evident, however, 15 that the flame issuing from the ports 23, although smaller than the upper flame, will be equally intense, owing to its natural tendency to travel upwardly.

24 designates a receiving-table which may, although not necessarily, be employed for the 20 reception of the stocking or other article after being singed.

To support the stocking or other article from within, so that it can be passed through the machine in a flat condition, I employ a 25 form 25. (Shown in Fig. 4.) This form 25 is shown as an ordinary stocking-board, although it is understood that in accordance with my invention the means for supporting the stocking within may consist of any device inserted 30 within the stocking to support the same in a flat condition while it is being singed. The stockings are preferably stretched upon this form.

The operation is as follows: The stockings 35 to be singed are supported from within by the form 25, which is so thin that the flames readily reach those portions of the stocking lying over the edges, as well as the portions stretched over the sides of the form, the movement of the goods being sufficiently rapid to 40 prevent any injurious effects of the flames, and it will be obvious that no singeing action is had on the inside of the stocking contiguous to said former. The formers and the stockings 45 thereon are propelled in the direction of the arrows seen in Fig. 1 by the feed-rollers 2 and 3, and it will be seen that all the long surplus fibers or fly will be singed therefrom at one and the same operation, which is an important desideratum in this class of work, as 50 it saves much time and labor, and consequently greatly reduces the cost of the singeing operation. The upper feed-roller being mounted in yielding or cushioned bearings permits a 55 sufficient vertical movement to compensate for the thickness of the form and surrounding stocking and does not, therefore, mash or unduly press the same, but grips it with sufficient force to cause a forward feed between the 60 burners to the receiving-table 24.

It is obvious that by the use of the former the stockings will be supported in a practically rigid manner during the feeding and singeing operation.

65 It will be evident that the feed-rollers 2 and

3 can be duplicated or arranged in pairs in series and the burner-tubes 16 and 17 also duplicated without departing from the spirit of my invention, the feed-rollers being actuated in unison by any suitable means.

The vapor used in the burner-tubes can be taken from any suitable source of supply, and it will be evident that, if desired, the jet-openings 22 and 23 may be made the same size and the inlet to the lower burner-tube reduced, 75 which would result in supplying a less quantity of gas to this tube, whereby the size of the flame would be reduced.

Having thus described my invention, what I claim as new, and desire to secure by Letters 80 Patent, is—

1. In a singeing-machine, burner-tubes arranged on opposite sides of the path of the article to be singed, and feed-rollers for propelling said article between said burner-tubes, 85 whereby both sides thereof are singed at one operation.

2. In a singeing-machine, burner-tubes arranged to project jets of flame in opposite directions, said jets being out of alinement, feed-rollers located in proximity to said tubes, and means for actuating said feed-rollers. 90

3. In a singeing-machine, burner-tubes arranged to direct their flames toward each other, a suitable former over which the stockings to 95 be singed are stripped, and means for bodily moving said former and the surrounding stocking between the flames of the burner-tubes.

4. In a singeing-machine, a pair of burner-tubes arranged to project jets of flame in opposite directions, a suitable former over which the stockings to be singed are stretched, and by which they are supported in a flat condition, and means for feeding said former and surrounding stocking through the jets of flame, whereby both sides of the stocking are singed at one operation. 100

5. In a singeing-machine, burner-tubes having jets arranged to direct their flames toward each other, said jets being out of vertical alinement, a suitable former over which the stockings to be singed are stripped, and means for bodily moving said former and the surrounding stocking between the flames of the burner-tubes. 110

6. In a stocking-singeing machine, a pair of burner-tubes located in proximity to each other and each provided with jet-openings arranged to produce an upwardly and downwardly disposed flame respectively, a feeding-table at one end of the machine, a receiving-table at the other end thereof, and means for causing the article to be singed to travel from the feeding-table between said burner-tubes and to be delivered upon said receiving-table. 120

7. In a singeing-machine, burner-tubes arranged to direct their flames toward each other, a source of supply common to said tubes, means for regulating the admission of oxygen to said burner-tubes, a former over 130

which the stockings to be singed are stripped and means for bodily moving said former and its surrounding stocking between the flames of said burner-tubes.

5 8. In a singeing-machine, a pair of burner-tubes arranged to project jets of flame in opposite directions, a suitable former over which the stockings to be singed are stretched, and by which they are supported in a flat condition, feed-rollers for feeding said former and its surrounding stocking through the jets of flame, whereby both sides of said stocking are singed at one operation, shafts on which said rollers are mounted, and yielding bearings for one of said shafts.

10 9. In a singeing-machine, a pair of burners located in close proximity to each other and each provided with jet-openings arranged to produce an upward and a downward disposed flame, respectively, a feeding-table at one end of the machine and a receiving-table at the other end, and means for causing the article to be singed to travel from the feeding-table, between the burners, and to be delivered onto 25 the receiving-table.

15 10. In a stocking-singeing machine, burner-tubes arranged to direct their flames toward each other, a suitable former over which the stockings to be singed are stripped, whereby 30 the threads or fibers thereof are stretched or spread apart, the means for bodily moving said former and surrounding stockings between the flames of the burner-tubes, substantially as described.

35 11. In a stocking-singeing machine, a pair of burner-tubes arranged to project jets of flame in opposite directions, a suitable former over which the stockings to be singed are stretched and by which they are supported in a flat condition, and means for feeding said former and surrounding stockings through the jets of flame, whereby both sides of the stocking are singed at one operation.

40 12. The combination in a machine for singeing the outside of hollow or tubular articles, such as stockings, of singeing means, and means for supporting the article from within, said means being relatively movable to apply the singeing means to the article.

45 13. The combination in a machine for singeing the outside of hollow or tubular articles, such as stockings, of singeing means, means for supporting the article from within, and means for moving said article - supporting 50 means relative to said singeing means to apply the singeing means to the article.

55 14. The combination in a machine for singeing the outside of hollow or tubular articles, of movable means for supporting the article

from within, and singeing means situated on 60 opposite sides of the path of said article-supporting means to apply the singeing means to the article.

15. In a machine for singeing the outside of hollow or tubular articles, such as stockings, 65 means for supporting the article from within and in a flat condition, and singeing means for applying the singeing agent to both sides thereof, said means being relatively movable.

16. In a machine for singeing the outside of 70 hollow or tubular articles, such as stockings, singeing means, and a form that is adapted to be inserted within the article to be singed, said means and form being relatively movable to apply the singeing means to the article. 75

17. In a machine for singeing the outside of hollow or tubular articles, such as stockings, burners arranged to direct their flames toward each other, a form that is adapted to be inserted within the article to be singed, said 80 burners and form being relatively movable in a path that will bring the burners on opposite sides of the form.

18. In a machine for singeing the outside of hollow or tubular articles, such as stockings, 85 burners for directing their flames toward each other, a form that is adapted to be inserted within the article, and means for bodily moving said form and surrounding article between the burners. 90

19. The combination in a machine for singeing the outside of hollow or tubular articles, such as stockings, of means for supporting the article from within, and means for singeing the outside of said article. 95

20. In a stocking-singeing machine, a suitable former for supporting the stocking, means for feeding the former and stocking through the machine, and means for singeing the external surface of the stocking during its passage therethrough. 100

21. In a stocking-singeing machine, a suitable former for supporting the stocking from within, means for feeding the former and stocking through the machine, and means for singeing the external surface of the stocking during its passage therethrough. 105

22. In a stocking-singeing machine, a suitable former for supporting the stocking fabric from within in a comparatively flat state, 110 means for feeding the former and stocking through the machine, and means for singeing the stocking during its passage therethrough.
